SCREENING AND COVERING DEVICE FOR
WINDOWS AND OTHER OPENINGS**Jay Rose, Brooklyn, N. Y., assignor, by mesne assignments, to Wardmore Corporation, a corporation of New York**

Application November 1, 1935, Serial No. 47,785

15 Claims. (Cl. 156—14)

My invention relates to screen devices for windows and the like, as described for instance in my copending application Serial No. 749,508 filed October 25, 1934, for Casement window screen, and has for its general object to provide new and improved devices of the character specified.

One object of the invention is to provide a two-part screen, the two parts of which are separately removable and replaceable and which when in place are so related to each other as to provide a complete and effective screen closure for the window or other type of opening.

Another object is to provide a two-part screen in which the parts are of different depths, the upper part, for example, being comparatively flat or shallow, and the lower part relatively deep or box-like, the lower part being provided with a screen door to facilitate access to the window latch or other hardware. This type of screen is particularly adapted to casement windows as are other features of the invention but it is to be understood that some of these features may be made use of in other connections than with casement windows. With this particular type of two-part screen the cost of frame material is reduced while the appearance is improved and the manipulation of window shades and drapes facilitated.

Another object of the invention is to provide screen devices which are particularly adapted to the hopper type of casement windows wherein there is a lower, or in some cases, upper portion of the window which is swingable about a horizontal axis for ventilation or other purposes independently of the main window section or sections which swing about vertical axes. My invention when applied to this type of casement window involves removable supports for inner and outer screen parts or screens, that for the hopper portion of the window being as herein shown an outer screen section which remains in a constant position and screens the hopper opening in all positions of the hopper window element.

Still another object of the invention is to provide novel catches or holding devices which while particularly adapted for use in connection with the window screens herein illustrated, are also capable of more general application.

While my present invention is adapted primarily for use with building openings having removable covers and particularly for casement windows, certain features of it are applicable to use with devices other than screens.

To the above and other ends which will subsequently appear, my invention resides in the features of construction, combinations of devices and arrangements of parts hereinafter described and particularly pointed out in the 5 claims.

The invention will be described and explained in detail in connection with the accompanying drawings, wherein

Fig. 1 is a front elevation of a double casement 10 window of the hopper type equipped with a screen according to the invention;

Fig. 2 is an enlarged vertical sectional view on line 2—2 of Fig. 1 with parts broken away, showing particularly the screen for the hopper portion of the window;

Fig. 3 is an enlarged vertical sectional view on line 3—3 of Fig. 1 with parts broken away, showing particularly a two-part screen for a casement;

Fig. 4 is a horizontal sectional view on line 4—4 of Fig. 2;

Fig. 5 is a horizontal section of the upper shallow screen on line 5—5 of Fig. 3, partly broken away; and showing how the screen is secured by 25 catches;

Fig. 6 is a view in perspective of a catch or clip shown in Fig. 5;

Figs. 7 and 8 show modified forms of such catches or clips;

Fig. 9 is a horizontal section on line 9—9 of Fig. 3, showing clips which hold the box-like structure of the lower screen;

Fig. 10 is a detailed view of a holding clip and retaining means in position on the box-like 35 frame of Figs. 3 and 9;

Fig. 11 is a view in perspective of the clip itself of Fig. 10;

Fig. 12 shows a modified form of retaining means for the clip of Fig. 10;

Fig. 13 is a front elevation of a double casement window wherein glass or the like is substituted for the wire screens of Fig. 1;

Fig. 14 is an enlarged vertical sectional view on line 14—14 of Fig. 13 with parts broken away;

Fig. 15 shows a modified form of the lower box-like screen of Fig. 3;

Fig. 16 shows a further modification of the catch shown in Fig. 6.

In the several figures of the drawings like reference characters indicate like parts.

Fig. 1 and its vertical section 3—3 shown in Fig. 3, taken together show the construction of the two-part screen for the casement and means 55

for removably securing the same to the casement window frame. Fig. 1, its vertical section 2—2 shown in Fig. 2 and horizontal section 4—4 of the latter shown in Fig. 4 taken together, 5 show the construction of the screen for the hopper portion and the means for securing said screen to the hopper window frame.

In connection with Fig. 3, Figs. 9, 10, 11, 12 and 15 show details and modifications of securing 10 means for the lower box-like portion of the two-part screen. Also in connection with Fig. 3, Figs. 5, 6, 7, 8 and 16 show details and modifications of securing means for the upper shallow portion 15 of the two-part screen.

Figs. 13 and 14 are similar to Figs. 1 and 3, 20 respectively, but show a two-part storm window instead of the two-part screen of the latter figures, no hopper portion being shown. Fig. 14 also shows how the lower part of said storm window or screen may rest upon the window sill.

Referring to the drawings by reference characters, the numeral 1 designates generally, 25 throughout the drawings the metal frame of a casement window which is built into the wall of a house. Such frames are usually of Z-shape section, as shown in Fig. 2. The window of Fig. 1 comprises two vertical casement windows 2 opening outward (only one of which is visible) and a hopper portion, opening inward, which 30 extends across the lower portion of the frame 1. Each window is provided with a latch 3 for locking it closed. Each casement swings on vertically aligned hinges such as 4 in Fig. 2.

According to the present invention a two-part 35 inside screen is removably secured to each of the casement windows of Fig. 1, said screen comprising a lower box-like part 5 and an upper, relatively shallow part 6. The wire screen 7 for the lower part is carried by a separate frame 8 40 hingedly secured to the box-like frame 5 whereby access may be had to the latches 3 for operating the casements. Suitable securing means 9 is provided for holding the door frame 8 in closed position. The upper wire screen 11 is secured 45 in frame 6 which rests on the lower box-like frame 5.

The details of the frames and screens above-mentioned are better shown in sectional Figs. 2 and 3.

The box frame 5 is preferably of channel section 50 as shown in Fig. 3 and comprises a bead 12 extending around the frame for stiffening purposes. The wire screen 7 is attached to its frame 8 and the latter is hinged to the box frame 5 by means well known in the art.

The bottom 19 of frame 5 rests upon a special 55 clip 13 whereby it not only is supported but is definitely positioned relative to the top of flange 14c of the Z bar forming part of the window frame between the casements and the hopper portion. The clip 13 comprises a U-shaped portion 16 of thin metal fitting snugly over the flange 14c, and also has a relatively wide horizontal portion for supporting the frame 5. Preferably 60 a portion of the inside flange 17 of frame 5 is cut away to provide room for the top 18 which extends somewhat above the horizontal portion of clip 13. By thus providing a cut-out portion for the clip 13 it is registered with the frame 5 so that it cannot move laterally with respect 65 thereto. It is understood, of course, that one or more clips may be provided depending to some extent on the width of the window, each clip preferably having a length of only a few inches 70 75 as shown at 13 in Figs. 1 and 9.

From the above it will be apparent that the frame 5 rests by its own weight on the clip 13 in such relation to the flange 14c that the window opening is substantially closed along this flange, it being understood of course that the horizontal portion of clip 13 may be somewhat lower relative to the top 18 of its U-shaped portion, thereby providing greater contact area between flange 14c and the flange 17.

In order definitely to secure the box frame 5 to the window frame there are provided according to the invention, in addition to the clip 13, a pair of detachable clips 20, one for each side of the frame. Such clips are shown in detail in Figs. 10, 11 and 12 as comprising a U-shaped portion 22 adapted to engage the vertical flanges 14e of the window frame. Each clip is provided with a closed slot 23 and an open slot 24. These slots are adapted to be engaged respectively by projections 26 and 27 struck out of the vertical portion of the flange 17. The upper slot 23 provides for movement of the clip 20 in any direction about horizontal projection 26, whereby the clip may be raised and swung inward when the box 5 is first positioned on the clip 13. Then the clip 20 is rotated until it engages the window flange 14e and is in a vertical position, whereupon it may be caused to slide downward so that the slot 24 engages the vertical projection 27, thus rigidly securing the clip and also the frame 5 to the window frame. Slot 24 is only sufficiently wider than the thickness of the metal of 27 to make a sliding fit therewith.

Fig. 9 shows in horizontal section the relation 35 of the clips 13 and 20, respectively, to flanges 14c and 14e, and to the box 5, whereby said box is held with its all-around flange 17 pressed against the faces of flanges 14c and 14e.

Each frame 5 will, of course, require a left-hand and a right-hand clip 20 and, in order to 40 prevent these clips from being lost or interchanged when the screens are put up and taken down, a Z-shaped spring 28 is secured to the flange 17 and resiliently bears against the top of projection 26. Clips 20 are therefore prevented 45 from being accidentally lost but they are easily removable by a slight bending out of the springs 28. A front view of the relative location of clip 20 and spring 28 is shown in Fig. 10. As a modification, a more permanent holding means 50 is shown in Fig. 12 whereby the struck-out projection 26 is provided with a hole and an additional projection is provided at 29 in the flange 17. Projection 29 is provided with a hole in alignment with the hole in 26. A short piece of 55 wire 31 may then be passed through the two holes and bent so as definitely to prevent removal of the clip 20 unless the wire 31 is first removed.

Referring further to Fig. 3, the upper flat 60 screen 6 rests by its own weight upon the top of box 5 and may be registered therewith by means of one or more pairs of detents 32, 33. Frame 6 is provided with an all-around flange 34 the edges of which are bent back upon themselves for stiffness and to eliminate a raw edge. 65 Frame 6 is held in contact with the flanges 14e and 14d of the casement window frame by means of catches positioned approximately in the center of each vertical side of the frame 6. These catches are shown more clearly in Figs. 5 and 6 70 75 80 wherein they comprise a bowed securing portion 36 and a laterally bent, hooked spring 37 rigidly secured to 36 or integral therewith. The catches are rigidly secured to the flange 34 by rivets, welding or other suitable means. The height of 75

members 36 should be such as to space their oppositely disposed bowed portions a less distance apart than the width of the opening between flanges 14e so that one spring 37 can be engaged with the flange 14e on one side and permit the other spring 37 to pass through the opening past the other flange. Then the screen 6 may be centered by sliding it laterally, leaving approximately equal spaces between springs 37 and the edges of flanges 14e, respectively. The centering is assisted and made almost automatic by means of the detents 32 abovementioned. Finger rings 35 may be provided on opposite sides of the screen for ease in handling.

15 Instead of the catches shown in Figs. 5 and 6, modified forms of catches may be provided such as shown in Figs. 7 and 8.

In Fig. 7 the catch consists of a bent wire or rod 38 passing through the front face of the frame 6, the straight portion passing through having a smaller diameter than the bent portion, whereby a shoulder surface is provided on the frame 6. A tubular member 39 with integral flanged extensions 39a is secured to flange 34, the tubular portion providing a bearing for rod 38. A laterally extending latch 40, is slipped over the small end of rod 38 and secured thereto, such as by pin 41.

20 With catches such as shown in Fig. 7 the frame 6 is positioned relative to box 5 and against the flanges 14d and 14e with the laterally extending latches 40 in a vertical position. Then, by giving rods 38 a quarter turn, the latches 40 engage the respective flanges 14e, thus holding the screen frame 6 securely in position.

25 In Fig. 8 a very simple form of clip 43 is rigidly secured to one side flange 34 of frame 6. This clip has a U-shaped portion that fits over and engages the flange 14e. Only one side of frame 6 is provided with a clip 43 because provision must be made on the other side of the frame for passing a catch through the window opening. Hence the clip 43 is used in combination with one of the catches shown in Figs. 5 and 7 on 30 the other side of the screen.

35 With the catches or holding means shown in Figs. 7 and 8, screen 6 may be definitely positioned laterally relative to the window frame, hence the detents 32 and 33 for registering with the box 5 may be omitted.

40 Another modification of holding means for the frame 6 is shown in Fig. 16 wherein one or more spring clips 44 are secured to the top flange 34 of frame 6 instead of to the side flanges thereof as in Figs. 5, 7 and 8. These spring clips 44 are adapted to hook around the flange 14d of the top Z-bar of the window frame. The combined height of the screen frames 5 and 6 should be such that top flange 34 bears against flange 14d 45 a short distance above its lower edge as shown in Fig. 16. To install this type of screen frame the clips 44 are engaged with flange 14d while the frame 6 is tilted at a sufficient angle to give the necessary clearance over box 5. Then the frame 6 is pushed slightly upward against the resiliency of springs 44 and rotated about its upper edge to a vertical position, whereupon it slips into its proper position resting on the lower box 5. The detents 32 and 33 then prevent accidental displacement of the frame 6. It should be understood, of course, that the clip construction shown in Fig. 16 can be used only when the bottom of frame 5 is definitely positioned relative to the top of flange 14c (Fig. 3) because all 50 variations in dimensions must be accommodated

5 by the resiliency of springs 44. The opening in commercial window frames from the top edge of flange 14c to the bottom edge of flange 14d may vary about one-eighth of an inch, and the dimensions of the frames 5 and 6 may have less variation. Hence the spring clips 44 will accommodate such variations and may be used with bottom supports for frame 5 as shown in Fig. 3 or 15, the latter figure being described below.

10 It is thus seen that the shallow upper part 6 of the screen may be readily and quickly removed without disturbing the lower box-like part 5 and that both parts of the screen are removably secured to the casement window frame without drilling holes or making any alterations in the latter.

15 In Fig. 3 it will be noted that a space is shown between the casement window 2 and the window frame 1, due to the thickness of the clips 20 and catches 37. It should be understood however 20 that this thickness is greatly exaggerated in the drawing and actually the metal is so thin that the somewhat resilient Z frames make a substantially tight contact. If the window or its frame is provided with a resilient weather strip, such 25 as rubber or the like, a weathertight joint will be secured.

20 Figs. 2 and 4 show the details of the screen for the lower, hopper-type window 45. Inasmuch as this window swings inward and slightly upward 30 on links 46, the screen is placed on the outside of the window. The screen frame 47 for this purpose is of the shallow type, similar to screen frame 6, and is provided with a wire screen 48. The all-around flange 49 of this screen is provided 35 with rounded edges which bear against the outside faces of the window frame flanges and are secured thereto by means of clips 20 constructed like the clips that hold the box-like frame 5. The weight of the screen 47 is supported and its position relative to the flange 14f 40 is determined by one or more Z-shaped clips 51 secured to the inside of the lower flange 49 of the screen and having a portion which engages the angle of flange 14f. The frame 47 is secured 45 in this position by the clips 20, the U-shaped portions of which engage the vertical flanges 14g of the hopper type window frame. Inasmuch as the frame 47 has a rounded edge rather than a flat flange bearing against the window frame, a 50 small angle piece 52 is affixed interiorly to each vertical side of the flange 49, the other leg of each angle having struck out projections 26, 27 and providing a support for the clip 20 and its retaining spring 28. The function and operation 55 of the clips 20 and the manner in which screen 47 is secured to the window frame are substantially as described above in connection with the box-like frame 5.

50 It should be understood of course that any of the modified forms of clips or catches may be used if desired on any of the screen frames.

55 Fig. 13 shows how the same general construction of frames 5 and 6 may be used for storm windows by providing them with panes of glass 65 or other transparent media 54 and 55, respectively, instead of wire screens 7 and 11. Otherwise the frames are constructed and secured to the window frame flanges in the same manner as the screens, as shown in Fig. 14.

70 Fig. 14 shows a modification that may be employed with either screens or storm windows when there is no hopper portion on the window and an inside window sill 56 is provided at a point somewhere on the face of, or below, the flange 75

14c. The clip 13 may then be omitted and the box-like frame 5 may be positioned directly on the sill 56. The combined height of the lower and upper parts of the frames should be such that the top flange 34 of the upper screen 6 has considerable overlap with the flange 14d to take care of varying heights of window sill relative to the flange 14c. Inasmuch as the clips 20 and catches 37, 40 and 43 engage vertical flanges 14e, their functions are unaffected by varying heights of window sill. When the frame 5 rests upon a window sill its bottom 10 may be made narrower, that is, it need not close the bottom of the box 5 as shown in Fig. 14 but may be only sufficiently wide to give the necessary stiffness.

Fig. 15 shows another modification wherein the bottom 10 of the box 5 is provided with one or more U-shaped portions 58 integral with the bottom, said U-shaped portions being adapted to slip over the top edge of flange 14c and thereby support the box 5 in definite relation thereto. With this construction a separate clip 13 is not needed.

From the foregoing description it will be apparent that the two-part screen provides ready access to the window and its hardware whereby it may be cleaned, opened and closed. The door in the lower screen provides such access without disturbing the box-like frame 5. The upper screen 6, being of light weight, shallow construction and separately detachable by grasping the finger rings 35 or handles 36, may be removed by a simple motion. Such removal need be only for cleaning the upper part of the window because the hardware and adjusting devices usually are on the lower portions of casement windows. Both sides of the hopper window are accessible from the inside of the house without disturbing the hopper screen 47. Hence it may remain in place throughout the summer season.

While several specific embodiments of the invention have been shown and described it should be understood that further modifications may be made such as to meet different conditions or uses, and therefore the appended claims are intended to cover all modifications within the true spirit and scope of the invention.

I claim:

1. A two-part window screen comprising a box-like part and a separate shallower part, said parts being separately removable and replaceable, and means attached to and solely carried by said parts for maintaining them in predetermined relationship in place on the window opening comprising fastening means on the box-like part detachably connecting it to the window opening and separate fastening means on the shallower part independently fastening it on said window opening above said box-like part.

2. A two-part window screen comprising a box-like part and a separate shallower part, said parts being separately removable and replaceable, and means for maintaining the parts in predetermined relationship in place on the window or other opening and with their vertical faces contacted with the window frame in substantially the same vertical plane comprising fastening means on the box-like part detachably connecting it to the window opening and separate fastening means on the shallower part independently fastening it on said window opening above said box-like part.

3. A two-part window screen comprising a box-like part and a shallower part, said parts being separately removable and replaceable, devices

cooperating with the window frame to secure each screen part individually in place thereon, and means for maintaining said parts in predetermined relationship to each other when in place.

4. A two-part window screen comprising a box-like part and a shallower part superimposed thereon, catches on each part for separately securing the parts to a window frame, the catches for the shallower part of the screen being secured to opposite sides thereof and having hooked portions extending inward from said sides sufficiently to permit sidewise movement of said shallower part to facilitate ready attachment and detachment, and cooperating projections and depressions in the contacting faces of the screen parts to maintain them in predetermined relationship when in place.

5. For use with a casement window frame, a two-part window screen, one screen part being a box-like window screen part provided with a relatively movable screen member, means mounted on said box-like part for detachably securing it to said frame, a support adapted to engage the lower flange of the window frame, the bottom of the said screen part normally resting on said support, and a relatively flat upper screen frame part adapted to be separately and detachably and independently secured to the window frame, and means for supporting said upper screen frame on the box-like window screen part in predetermined relationship therewith.

6. For use with a window, a frame, a flat element of suitable material arranged within said frame, and means for detachably securing the frame and the material carried by it to the window, said means comprising thin metal clips attached to said frame but freely rotatable respectively about fixed points thereon, and separate means on said frame for locking said clips in the position in which they secure the said frame.

7. A catch for window screens and the like comprising a bowed securing portion and a laterally bent, hooked spring portion rigidly secured to said bowed portion.

8. A catch for a window screen and the like comprising a bowed securing portion and a laterally bent hooked portion integral therewith, said hooked portion having inherent springiness and the bowed portion having means for securing it in place on the screen.

9. A catch for casement window screens and the like comprising a thin metal U-shaped plate formed at one side with parallel slots, and a support provided with oppositely disposed lugs cooperating with said slots to maintain the catch normally in a locked position.

10. A catch for casement window screens and the like comprising a thin metal U-shaped plate formed at one side with parallel slots, a support provided with oppositely disposed lugs cooperating with said slots to maintain the catch normally in a locked position, the catch being movable to disengage one of said lugs and swingable about the other lug when so disengaged.

11. A catch for casement window screens as defined in claim 10, and means on the said support for retaining the U-shaped plate on the lug about which it swings.

12. In combination, a metal frame adapted to cover an opening and a catch therefor comprising a U-shaped plate formed at one side with a closed slot and an open slot, lugs struck out from the metal of said frame and engaging the

respective slots, and resilient means secured to the frame and bearing on the lug that engages the closed slot.

5 13. In combination, a metal frame adapted to cover an opening and a catch therefor comprising a U-shaped plate formed at one side with a closed slot and an open slot, lugs struck out from the metal of said frame and engaging the respective slots, a third lug struck out from said frame, and means engaging said third lug and the lug in the open slot for retaining the U-shaped plate on the last mentioned lug but freely movable relative thereto within the limits of the closed slot.

10 14. In combination, a box-like window screen for a metal window frame, and a pair of U-shaped clips removably attached to opposite inner sides of said screen and swingable about

fixed points on the screen, said clips being adapted to secure the screen to the side flanges of the window frame when the clips are vertical, and means on said screen for engaging said clips and locking them in a vertical position.

15 15. For use with a casement window frame, having an inwardly opening window portion, a screen for said portion adapted to be secured to, and supported from, the window frame exteriorly of said portion and in predetermined position relative thereto, said screen having clips mounted on opposite sides thereof and rotatable to engage simultaneously the screen and the window frame, and a support rigidly secured to the bottom of said screen and adapted to engage the bottom of the window frame for supporting the screen in predetermined position as aforesaid.

JAY ROSE.
